UNITED STATES PATENT OFFICE.

WOLF. FLECHTER, OF COVINGTON, KENTUCKY.

METHOD OF AND MEANS FOR STUFFING DOLLS.

SPECIFICATION forming part of Letters Patent No. 371,751, dated October 18, 1887.

Application filed July 14, 1887. Serial No. 244,295. (No model.)

To all whom it may concern:

Be it known that I, WOLF. FLECHTER, a citizen of the United States, residing at Covington, in the county of Kenton and State of Kentucky, have invented a new and useful Improvement in Methods of and Means for Stuffing Dolls, of which the following is a specification.

My invention relates to a method of and means for stuffing dolls, and has special reference to filling the body and members of the doll with fleecy or fibrous material—such as cotton-wool, hair-filaments, and the like—all as hereinafter described, illustrated in the drawings, 15 and specifically pointed out in the claims.

Referring to the accompanying drawings, in which like letters or reference point out similar parts, on each figure, Figure 1 represents the method of stuffing a doll-form according 20 to my invention, the devices employed being shown partly in elevation and partly in section. Fig. 2 is a top plan view of Fig. 1 with the form removed. Fig. 3 is a view of a modified locking device for the binding-ring.

25 In describing my invention I shall employ the word "form" as meaning and including the trunk, legs, arms, and all members of the doll made hollow, and adapted, when stuffed, to be extended to the suitable configuration 30 which is assured by the shape of the several blanks of textile fabric which, when sewed together, constitute the doll-casing.

In order to fully explain my invention and the manner of practicing the same, I will first 35 describe the ordinary manner of stuffing forms prior to my improvement, and then point out the advantages secured by my improvements.

Prior to my invention it has been the practice for the operator to hold the empty form 40 in one hand, then to insert in the openings thereof a funnel-shaped device, then to pick up with one hand from time to time a quantity of the stuffing material, and then to ram down said substance with a rod or plunger, 45 repeating the several steps until the form is shaped. Intermediately the rod is forced within the form by pressure against the operator's body. As most operators are girls and young women, the manipulation in this manner is obviously objectionable. In ramming

down the form the operator's head is bent forward and the chest becomes the fulcrum. The stuffing material contains dust, fibers, and divers substances light in weight, that are expelled outwardly, and there is in consequence 55 an ever-present cloud of filaments charged with pigments, fibers, dust, and deleterious floating particles, which are drawn into the mouth and nostrils. The resulting injury to health is serious and often irremediable. 60

I will observe that it requires considerable force to pack the stuffing within the form. The employment of both hands for this purpose is very desirable. A sitting position, whereby one hand has to be employed holding 65 the form, is therefore objectionable. It will, moreover, be understood that the old process is slow and tedious. For example: First, the empty form is grasped in one hand. Then the funnel is introduced into the open end of the 70 form. Then a quantity of stuffing material is picked up and loosely dropped into the funnel. Then the plunging-stick is picked up and the mass rammed down, and so on alternately are these slow and tedious steps repeated. I will 75 observe that when the material employed for stuffing is grasped in the hand portions thereof frequently remain sticking to the skin, and in many cases incurable cutaneous diseases are thereby acquired. It is by the old process difficult to keep the mass from becoming lumpy. Portions will be packed hard and dense, while other parts will be loose and attenuated; and experience has demonstrated that the utmost skill 80 and expertness are required to insure acceptable work; but before the operator becomes accustomed to the work, in most cases, further employment is declined on account of injury to health, as heretofore set forth. To overcome these objections and to provide an easy, 85 expeditious, and inexpensive method of stuffing forms has been the object of my invention. 90

To the accomplishment of my purpose my invention consists in devices whereby the 95 operator can, while in a standing position, fill the form without handling any of the stuffing material. The tool I have provided for this purpose is adapted to grasp a given quantity of the stuffing, insert it within the form, 100

and press it into position vertically and laterally at one operation.

In the drawings, A is the form, composed of textile material; B, a table adapted to be firmly attached to any suitable support. (Not shown in the drawings.) Said table is supplied with one or more openings, b. To said opening is rigidly attached a lining or tube, b', flush with the bottom of the table, but ⁵ ¹⁰ rising above the upper surface thereof, forming an upwardly-extending collar or ring, as plainly shown in Fig. 1.

C is a binding-ring having an upper turned-over edge, forming a peripheral bead, c', to impart rigidity thereto. Said ring at its lower part is preferably supplied with one or more outwardly-extending lugs, C', cut away at one side to form a bayonet-slot, c², for a purpose presently set forth.

20 Upon the upper surface of the table are studs or screws b³, with which the bayonet-slots mesh, and, as will be readily understood, I thereby provide means for locking and unlocking the binding-ring. Fig. 3 shows a ¹⁵ ²⁵ modified form for holding down the binding-ring vertically, consisting of swinging braces c⁴, hooked to staples c⁵, attached to the table B. These braces can be employed separately or in conjunction with the bayonet-slot locking device heretofore described.

D is a combined grasping and ramming tool in the form of a pair of tongs, which during the stuffing process is held in one hand. When considerable force is required, the other ³⁵ hand can also be brought to overlap the handles, and both hands be employed to ram down the stuffing. (See dotted lines, Fig. 1.)

In carrying out my process for stuffing the form the free end thereof is passed through ⁴⁰ the opening b, inside the lining b', and returned over its upper edge outwardly, a portion of said form passing downwardly outside of the upper extension of said lining. The binding-ring is then passed over the overlapping portion of the form, whereby it is firmly held by ⁴⁵ said ring and the inner concentric extension of the lining b'. The ring C is then locked firmly in position, as before described, and the

device is ready for the stuffing process. With one hand the operator takes hold of the tool D and grasps with the ends of its blades a quantity of the stuffing. The tool is then inserted within the hollow form A and the material is deposited in proper position, (not loosely dropped therein.) The process of ramming is thereby measurably reduced. The operation is repeated until the form has assumed its proper configuration.

When the packing is not completely accomplished, the blades d d can be employed to ram the substance vertically, or by extension of said blades, which are pivoted together, to press it laterally. If the force of one hand is insufficient, both can be employed. (See dotted lines, Fig. 1.)

From the foregoing description, in connection with the drawings, my invention and the manner of practicing the same will be fully understood by all skilled in the arts to which it is allied.

Having now fully described my invention, what I claim, and desire to secure by Letters Patent, is—

1. In a device for stuffing dolls, the table B, having opening b, provided with permanently-⁷⁵ attached lining-ring b', extending above the upper plane of said table, the removable binding-ring C, having lower notched flanges, C', in combination with studs b³, as and for the purpose intended, substantially as described.

2. The within-described process for stuffing dolls, which consists of the following steps: first, suspending the form by its upper edge from a table, then picking up from a receptacle with a pair of tongs a quantity of stuffing substance, then introducing said grasped material direct into its proper place within the form, and then, without withdrawing said tongs, firmly compressing said stuffing material vertically and laterally by action of said tongs, ⁸⁵ ⁹⁰ substantially as described.

WOLF. FLECHTER.
